CLAIM

The ornamental design for a pet litter scoop, as shown and described.

DESCRIPTION

FIG. 1 is a side, top, perspective view of the pet litter scoop with a rake portion and a handle portion shown in phantom. The portions shown in phantom are intended to show environment for, and form no part of, the claimed design.

FIG. 2 is a top view thereof;

FIG. 3 is a left-side view thereof, the right-side view thereof being a mirror image of the left-side view thereof;

FIG. 4 is a front view thereof;

FIG. 5 is a rear view thereof; and,

FIG. 6 is a bottom view thereof.
